CLAIM

The ornamental design for automotive interior mat with stripe, as shown.

DESCRIPTION

FIG. 1 is a perspective view of a automotive interior mat with stripe showing my new design;

FIG. 2 is a front elevational view thereof;

FIG. 3 is a rear elevation view thereof;

FIG. 4 is a side elevation view thereof;

FIG. 5 is a side elevation view thereof;

FIG. 6 is a side elevation view thereof; and,

FIG. 7 is a side elevation view thereof.

The broken lines shown illustrate portions of the automotive interior mat with stripe that form no part of the claimed design.
